UNITED STATES PATENT OFFICE.

JOHN A. SKEDGELL, OF READING, PENNSYLVANIA, ASSIGNOR TO DRAPER CORPORATION, OF HOPEDALE, MASSACHUSETTS, A CORPORATION OF MAINE.

BUILDER MECHANISM FOR SPINNING OR WINDING MACHINES.

Application filed April 7, 1927. Serial No. 181,820.

This invention relates to builder mechanisms for spinning or winding machines, and is more particularly concerned with such mechanisms which are provided with 5 a bunch building attachment.

It is now the ordinary practice to provide filling carriers or bobbins which are to be employed in "feeler looms" with preliminary windings, technically known as a "bunch"

10 to provide on the filling carriers or bobbins a reserve supply of yarn to insure laying a full pick of filling in the shed on the last pick of the shuttle prior to filling replenishment, and many forms of builder mechanisms with bunch building attachments have 15 been devised for this purpose. The present invention, however, is a further development of the builder mechanisms shown and described in the Horace H. Burdett Patents, Numbers 1,556,814, dated October 13, 1925; 1,556,815, dated October 13, 1925, and 1,579,190, dated March 30, 1926, wherein a worm carried by the builder arm and having both rotary and transverse movements relative thereto, cooperates with a bunch building device or disk rotating with the main builder cam, and in such constructions the worm on the builder arm is moved by the 20 rotary bunch building device out of operative relation therewith on completion of the bunch, whereupon regular traverse is initiated.

In providing filling carriers or bobbins with the reserve supply of filling or bunches, 25 due regard must be had to the width of the loom in which such filling carriers or bobbins are to be employed for laying the filling in the shed, and likewise it is desirable in connection with certain feeler mechanisms 30 employed in feeler looms to position the preliminary windings or bunches at different portions of the filling carriers or bobbins, sometimes near the head of the filling carriers or bobbins, and at other times more 35 remote therefrom.

One of the important features of the present invention consists in a builder mechanism having a bunch builder attachment which may be readily associated with spinning or winding machines now in general use and wherein the amount of yarn constituting such bunches may be varied to suit the conditions of the loom in which such filling carriers or bobbins are employed, 45 and another important feature of the pres-

ent invention consists in the ready adaptation of the builder mechanism to place the bunches on filling carriers or bobbins at different positions along the barrels of the filling carriers or bobbins to thereby adapt 60 such filling carriers or bobbins for use with different kinds or characters of feeler mechanisms.

In accordance with the present invention, the main builder cam for laying regular 65 service traverse is loosely mounted, and when the bunch builder mechanism is operating to build the bunch, such main builder cam remains idle and in a predetermined position, and is given rotary movement on 70 the completion of the bunch to initiate regular service traverse.

In accordance with another feature of the present invention, the main builder cam is held in non-rotative and predetermined position with a low part of the cam opposite the cam follower on the builder arm during the bunch building operation, and the worm which is carried by the builder arm, and its cooperating bunch building device, are relatively adjustable towards and from each other to vary the position of the bunch on the bobbins in accordance with the character of feeler mechanism employed in the loom.

The invention and new features thereof and novel combination of parts will best be made clear from the following description and the accompanying drawings of one good form thereof, it being understood that variations may be made in details without departing from the true scope of the invention as defined by the claims.

In the drawings:

Fig. 1 is a perspective view of a part of a spinning or winding machine, showing more particularly the builder mechanism of the present invention associated therewith;

Fig. 2 is a side elevation on an enlarged 100 scale showing the relation of parts during the bunch building operation;

Fig. 3 is a front elevation showing more 105 particularly the relation of parts during the bunch building operation;

Fig. 4 is a section on the line 4—4 of Fig. 2;

Fig. 5 is a section on the line 5—5 of Fig. 4, showing the predetermined position of the main builder cam and its relation to the 110

cam follower on the building arm during the bunch building operation;

Fig. 6 is a section on the line 6—6 of Fig. 4;

5 Fig. 7 shows a filling carrier or bobbin with the bunch on the barrel thereof at a point remote from the head of the filling carrier or bobbin; and

10 Fig. 8 is a view similar to that of Fig. 7 but showing the bunch adjacent the head of the filling carrier or bobbin.

The frame 1 of the spinning or winding machine may be of usual construction, and, as shown, the side frames thereof are connected by the cross-girths 2 and 3, the upper one of which may constitute the usual spindle support on which a series of spindles for receiving the filling carriers or bobbins are mounted for rotative movement, and, as indicated in the present instance, such spindles are rotated by means of the band 4 and rotating tin drum 5, although, as will be apparent, any suitable means may be employed for giving rotative movement to the spindles.

25 The spindles 6, which, as before stated, are mounted for rotative movement on the spindle rail 2 and receive the filling carriers or bobbins on which yarn is to be wound, extend upwardly through the ring rail 7, on 30 which the usual spinning rings 8 and travelers 9 are mounted, the rings and travelers constituting guiding means for the yarn in laying it upon the filling carriers or bobbins. The ring rail 7 is supported on the rods 10, of which there may be a suitable number, and the lower ends of such rods 10 rest upon a pin or roll 11 mounted on the arm 12 which is pivotally supported at 13 upon a bracket 14, such arms 12 being under 35 the influence of a weight 15 normally tending to lift the ring rail. Connected with the arms 12 (one only of which is shown in the present instance) is the segment 16 to which is secured the flexible connection 17 which 40 extends over the guide pulley 18 and is connected at its lower end to the builder arm. It is usual in mechanisms of this general type to let back on the flexible connection 17 during the regular traverse, in order to lay 45 the yarn in conical layers upon the filling carriers or bobbins, and one means of effecting this purpose is shown more particularly in Fig. 2.

The builder arm 19 is pivotally mounted at 20 and is normally under the influence of a weight 21 tending to lift the outer or free end of the builder arm, as usual in this class of machines. The let-back mechanism herein shown consists of an arm 22 pivotally mounted at 20 and the outer end portion of which at 23 is connected with the flexible connection 17, thereby associating the builder arm with the traverse mechanism or ring rail. The builder arm as herein shown in the present instance of the invention is pro-

vided with a segmental guide 24 in which is mounted the toothed rack 25 having a roll 26 which acts upon the curved portion of the arm 22 to effect a let-back on the flexible connection during main service traverse. 70 The teeth of the rack 25 are operatively engaged with a worm 27 on the pick shaft 28, to the outer end of which is connected the pick wheel 29 which is actuated step-by-step during the swinging movement of the builder arm to move the rack 25 and effect let-back upon the flexible connection 17. This mechanism is merely one of the types of builder arm and let-back mechanism that may be employed in connection with the present invention, although any other character of builder arm and let-back mechanism may be used, since the details thereof form no part of the present invention.

75 The main builder cam shaft 30 is suitably mounted in the machine frame for rotative movement, and such rotative movement is imparted to the main builder cam shaft through any suitable train of mechanism connected with a going part of the machine, but since such actuating mechanism of the main builder cam shaft may be of usual construction now well understood in the art and since the details thereof constitute no essential part of the present invention, such actuating mechanism for the cam shaft is not herein shown and described.

80 The main builder cam 31 is loosely mounted upon the rotating shaft 30 and during bunch building operation, as will later appear, such main builder cam is held in non-rotative predetermined position and on completion of the bunch the main builder cam is actuated to initiate in connection with the cam follower 32 on the builder arm 105 the regular service traverse. Any suitable means may be employed for predeterminate- 110 ly positioning the main builder cam in rotative position during the bunch building operation, and as one good form of means to this end, the main builder cam 31 has connected thereto one or more weights, as herein shown, which, when the main builder cam is freed for rotative movement, turn the main builder cam into the predetermined position desired.

115 As shown in the present instance of the invention, the main builder cam has secured thereto a depending arm 33, and, as shown in the present instance, such connection between the arm 33 and the main builder cam 31 is effected by means of a bolt 34 which carries a weight 35, the construction being such that when the main builder cam is free for rotative movement it will be turned 120 rotatively into the predetermined rotative position. The weighted arm 33 may be sufficient in itself to effect this rotative movement of the loosely mounted main builder cam, but, in the present instance of the inven- 125

tion, the builder cam is shown as provided with a further weight 36 which in connection with the weight 35 relatively positions the main builder cam during the bunch building operation, so that a low portion of the cam, as at 37, shall be opposite the cam follower 32 as indicated in Fig. 5. The hub portion of the arm 33 is utilized in the present instance of the invention to prevent movement of the main builder cam 31 longitudinally of the rotating main builder cam shaft 30, and to this end the hub portion of the arm 33 is provided with a pin of lug 38 which engages a groove in the stationary projection 39 which may be appropriately secured to the machine frame 1.

Mounted upon the driven main builder cam shaft 30 for rotative movement therewith and for movement laterally thereon is 20 a bunch building device, which as shown is constituted as a scalloped disk, in order to impart short traverse movements to the bunch during the bunch building operation, at which time the main builder cam is idle. 25 as hereinbefore stated. In the present instance of the invention, the bunch building device 40 is connected with a hub portion 41 splined to the driven main builder cam shaft 30, and, in the present instance of the invention, such splined connection is afforded 30 by means of a pin 42, the ends of which project beyond the cylindrical surface of the cam shaft and engage suitable grooves 43 in the hub of the bunch building device 40. 35 the result being that the bunch building device 40 is rotative with the main builder cam shaft and is movable longitudinally thereof into and out of bunch building position, as will later appear.

40 The hub portion 41 of the bunch building device is provided with a groove 44 which is engaged by pins 45 on the yoke 46 pivotally mounted at 47 and connected to a hand or other lever 48, the construction being such that while the bunch building device 40 may rotate with the main builder cam shaft, it may be moved longitudinally thereof by the manually operated means 48.

45 The end portion of the hub 41 of the bunch building device is provided with a clutch member 49 adapted to engage with a complementary clutch member 50 secured to the main builder cam 31, the construction being such that when the bunch building device 40 is moved laterally away from the main builder cam by the manually operated lever 48, the clutch members will be disengaged, thereby freeing the main builder cam and permitting the weights connected thereto 50 to turn the main builder cam into a predetermined position to locate the low portion 37 of the builder cam opposite the cam follower 32 on the builder arm 19, and owing to this fact, also, the diameter of the bunch building device 40 may be made relatively smaller in 55 diameter.

Secured to the builder arm by suitable 60 means, such as the bolts 51, is a bracket 52

having a laterally extending portion 53 and an upwardly extending portion 54, the latter of which is provided with an upwardly extending slot 55.

Mounted for vertical adjustment in the slot 70 55 is the worm supporting pin 56 which may be secured in adjusted position in the slot 55 by clamping means, such as the nuts 57, which may be appropriately threaded to the worm supporting pin 56. 75

In accordance with the present invention, the worm 58 is mounted upon the worm supporting pin 56 and is confined to rotary movement thereon; that is, it has no movement longitudinally of the worm supporting 80 pin. One appropriate means of effecting this result consists in providing the pin 56 with a barrel portion 59 on which the worm 58 is mounted, the inwardly extending flange portions 60 of the worm confining the worm 85 from movement longitudinally of the pin in one direction. Secured to the worm 58 is the weight 61 which may be appropriately connected to the worm by means of a screw 62, and the face of such weight 61 bears upon 90 the end portion 63 of the barrel portion 59, with the result that the worm is freed for rotative movement on the worm supporting pin 56 but is confined from movement longitudinally thereof. 95

Inasmuch as the main builder cam is automatically positioned rotatively to place the low part of the cam 37 opposite the cam follower 32 during the bunch building operation, it follows that the worm supporting 100 pin 56 may be adjusted in the slot 55 upwardly or downwardly relative to the bunch building device 40, with the result that the location of the bunch on the barrel of the filling carriers or bobbins may be in desired 105 position. When the worm supporting pin 56 is adjusted upwardly in the slot 55 and towards the bunch building device 40, the bunch *a*, as indicated in Fig. 8, will be located near or adjacent to the head of the filling carrier or bobbin, but when the worm supporting pin 56 is adjusted downwardly in the slot 55, the bunch *b*, Fig. 7, will be located on the barrel of the filling carriers or bobbins at a point remote from the head 110 thereof. This adjustable characteristic of the worm upwardly or downwardly relative to the builder arm to vary the location of the bunch is rendered possible by the fact that during the bunch building operation the 115 main builder cam is idle and the low part 37 of the cam is opposite the cam follower 32 on the builder arm 19, and owing to this fact, also, the diameter of the bunch building device 40 may be made relatively smaller in 120 diameter.

The size of the bunch will depend upon the relative lateral positions of the bunch building device 40 and the worm when they are in bunch building positions. As one 130

good means for effecting this variation in the size of the bunch, a stop is provided for limiting the lateral movement of the bunch building device 40 on the main builder cam shaft 30, and, as shown in the present instance of the invention, such stop consists of a sleeve 64 which may be secured in adjusted position laterally of the main builder cam shaft by means of a set screw 65, whereupon the end portion 66 of the sleeve will be positioned to determine the lateral movement of the bunch building device 40 under the manual manipulation of the hand lever 48.

When a series of filling carriers or bobbins have been completely wound and the ring rail or yarn guides are lowered and held in lowered position for doffing, as usual, and are substituted by a fresh series of unfilled filling carriers or bobbins, the machine attendant manipulates the hand lever 48 thereby moving the bunch building device 40 laterally along the main builder cam shaft 30 until it contacts with the stop 66 which determines the part of the worm 58 that will be engaged by the bunch building device 40 when the ring rail or yarn guides are freed from their holding means and the builder arm is raised, thereby determining the amount of yarn that will be placed in the bunch. Such movement of the bunch building device 40 also disengages the clutch numbers 49 and 50 and frees the main builder cam, which will then assume a predetermined position rotatively, as determined by the weights 35 and 36, so that during bunch building operation the main building cam is idle. When the machine is started, the bunch building device 40 rotates the worm 58 which acts upon the bunch building device 40 to move it laterally towards the main builder cam, and on completion of the bunch, the bunch building device moves laterally out of engagement with the worm and simultaneously therewith engages the clutch members 49 and 50 so that the main builder cam then becomes operative to lay regular service winds.

It is sometimes desirable to facilitate the movement of the bunch building device 40 laterally towards the main builder cam in addition to the movement imparted thereto by the worm, and for this purpose a spring 67 mounted upon the hub portion 64 of the stop acts upon the bunch building device 40 to move it towards the main builder cam, so that on completion of the bunch the main builder cam and the bunch building device 40 are operatively related to cause rotative movement of the main builder cam to proceed with regular service traverse.

It is desirable that bunches placed upon successive series of filling carriers or bobbins shall contain the same amount of yarn con-

stituting the bunch, a condition that is rendered effective in the present instance of the invention by providing the weight 61 upon the worm 58 in order to turn the worm into the same rotative position each time it is disengaged from the bunch building device 40, so that upon reengagement of the bunch building device 40 and the worm, the two will engage at the same point and consequently the amount of yarn placed in the bunches of successive series of filling carriers or bobbins will be equal.

Where it is desirable to provide the layers of the bunch with a short traverse, the peripheral portion of the bunch building device 40 is made irregular or scalloped, as indicated in the present instance of the invention, so that during the bunch building operation the irregular edge or scallops on the bunch building device 40 will effect short traverse of the yarn during the bunch building operation.

From the construction described as a good practical form of the present invention, it will be noted that during the bunch building operation the main builder cam is held from rotative movement in a predetermined position, and on completion of the bunch as the bunch building device 40 is moved laterally by the worm out of bunch building position, the main builder cam will be operatively connected with the rotating bunch building device 40 to effect regular service traverse. Should no bunches be desired in any series of filling carriers or bobbins, the machine attendant does not actuate the hand lever 48 to move the bunch building device 40 into bunch building position, whereupon, the main builder cam remains in action and only service traverse is laid upon the filling carriers or bobbins.

As a further development of the builder mechanisms shown and described in the Burdett patents hereinbefore mentioned, the present invention provides a simple and effective means not only of varying the amount of yarn laid in the bunch, but, also, in locating the bunch at different portions of the filling carriers or bobbins, as indicated in Figs. 7 and 8.

While the clutch members 49 and 50 constitute a good practical means for operatively connecting and disconnecting the main builder cam and the bunch building device, it is clear that some other form of mechanism may be employed for this purpose and that detail changes may be made in the construction described to effect the desired purpose without departing from the actual invention as defined by the claims.

What is claimed is:

1. A bunch builder mechanism for spinning or winding machines, comprising, in combination, yarn guiding means, a builder arm for controlling the yarn guiding means,

5 a loosely mounted main builder cam, a rotating bunch building member movable towards and from the main builder cam, a clutch associated with the bunch building member
 10 for engagement with and disengagement from the main builder cam, a worm held from lateral movement on the builder arm, and means for moving the bunch building member into bunch building relation with the worm and disengaging the clutch from the main builder cam that the main builder cam may remain at rest during the bunch building operation.

15 2. A bunch builder mechanism for spinning or winding machines, comprising, in combination, a builder arm, a bunch building worm mounted for rotary movement on the builder arm, a loosely mounted main builder cam, a constantly rotating bunch building member movable laterally into bunch building relation with the worm, a clutch which is disengaged from the main builder cam during the bunch building operation and is automatically engaged with the main builder
 20 cam by lateral movement of the bunch building member by the worm to rotate the main builder cam on completion of the bunch.

25 3. In a spinning or winding machine, the combination of a rotating cam shaft, a main builder cam loosely mounted on the cam shaft, a building arm having a loosely mounted worm held from lateral movement, a bunch building member rotating with the cam shaft and normally clutched to the main builder cam during regular traverse, and means for laterally moving the bunch building member into bunch building relation with the worm and freeing the main builder cam and automatically clutching the
 30 main builder cam for rotary movement with the bunch building member on completion of the bunch.

35 4. In a spinning or winding machine, the combination of a loosely mounted main builder cam, a builder arm, a worm on the builder arm confined to rotary movement relative thereto, a rotating device to cooperate with the worm to build the bunch with a short traverse and movable laterally by the worm out of bunch building position on completion of the bunch, and means for causing the loosely mounted main builder cam to be rotated to complete the wind with regular service traverse on completion of the bunch.

40 5. In a spinning or winding machine, the combination of a loosely mounted main builder cam, a builder arm, a worm on the builder arm confined to rotary movement relative thereto, a rotating device having an irregular edge portion to cooperate with the worm to build the bunch with a short traverse and movable laterally by the worm out of bunch building position on completion of the bunch, and means for causing the loosely

45 mounted main builder cam to be rotated to complete the wind with regular service traverse on completion of the bunch.

6. In a spinning or winding machine, the combination of a loosely mounted main builder cam, a builder arm, a worm on the builder arm confined to rotary movement, a rotating disk having a scalloped edge to engage the spirals of the worm to build the bunch with a short traverse and movable laterally by the worm out of engagement therewith as the worm is rotated by the scalloped disk, and clutch means moved into operative engagement with the loosely mounted main builder cam by lateral movement of the scalloped disk out of bunch building position to rotate the main builder cam to complete the wind with regular service traverse on completion of the bunch.

7. A bunch builder for spinning or winding machines, comprising, in combination, a rotating cam shaft, a main builder cam loosely mounted thereon, a builder arm, a worm on the builder arm confined to rotary movement, a bunch building member splined to the rotating cam shaft and having an edge to cooperate with the worm to build the bunch and movable by the worm out of bunch building position, complementary clutch members on the main builder cam and bunch building member, and manual means for moving the bunch building member on the cam shaft into bunch building relation with the worm and for disengaging the clutch members.

8. In a spinning or winding machine, the combination of a main builder cam shaft, a main builder cam, a builder arm, a worm on the builder arm confined to rotative movement, a bunch building device rotating with the cam shaft and movable along said shaft into bunch building relation with the worm and movable by the worm out of bunch building position, a stop for defining the bunch building position of the bunch building device when it is moved along said shaft into bunch building position, and means for adjusting said stop to vary the size of the bunch.

9. In a spinning or winding machine, the combination of rotary main builder cam shaft, a main builder cam loosely mounted on the cam shaft, a builder arm, a worm on the builder arm confined to rotative movement, a bunch building device rotating with the cam shaft and movable along said shaft into bunch building relation with the worm and movable by the worm out of bunch building position, clutch means for operatively connecting the rotating bunch building device and main builder cam when the bunch building device is moved out of bunch building position by the worm, and a spring for insuring the clutch engagement of the rotating bunch building device and loosely

mounted main builder cam on completion of the bunch.

10. In a builder mechanism, the combination of a rotating cam shaft, a main builder cam, a builder arm, a worm on the builder arm confined to rotary movement, a bunch building device having an irregular edge and rotating with the cam shaft to cooperate with the worm on the builder arm to build the bunch and movable by said worm out of bunch building position, means for moving the bunch building device along said cam shaft into bunch building position, and an adjustable stop for limiting the movement of the bunch building device along the cam shaft into bunch building position to vary the size of the bunch.
11. A builder mechanism, comprising, in combination a builder arm, a worm carried by the builder arm and confined to rotary movement relative thereto, a rotating and cooperating bunch building device movable laterally into bunch building relation with the worm and movable by the worm out of bunch building position on completion of the bunch, a loosely mounted main builder cam which is held stationary during the bunch building operation, and means for operatively connecting the main builder cam with the rotating bunch building device when the latter is laterally moved by the worm out of bunch building position on completion of the bunch that regular service traverse may be initiated.
12. A builder mechanism, comprising, in combination a builder arm, a worm carried by the builder arm and confined to rotary movement relative thereto, a rotating and cooperating bunch building device movable laterally into bunch building relation with the worm and movable by the worm out of bunch building position on completion of the bunch, a loosely mounted main builder cam, a weight connected to the main builder cam and acting to maintain it stationary in predetermined position during the bunch building operation, and means for causing the main builder cam to be rotated to impart regular service traverse when the bunch building device is moved out of bunch building position by the worm on completion of the bunch.

13. In a builder mechanism, the combination of a builder arm having a cam follower, a worm carried by the builder arm and confined to rotary movement relative thereto, a cooperating bunch building device movable into bunch building relation with the worm and movable by the worm out of bunch building position on completion of the bunch, a loosely mounted main builder cam, means for holding the main builder cam from rotary movement and in predetermined rotary position during the bunch building operation, and means for

causing the main builder cam to be rotated on completion of the bunch to impart regular traverse.

14. In a builder mechanism, the combination of a builder arm having a cam follower, a worm carried by the builder arm and confined to rotary movement relative thereto, a cooperating bunch building device having an irregular periphery to impart a short traverse during the bunch building operation and movable into bunch building relation with the worm and movable by the worm out of bunch building position on completion of the bunch, a loosely mounted main builder cam, means for holding the main builder cam from rotary movement and in predetermined rotary position during the bunch building operation, and means for causing the main builder cam to be rotated on completion of the bunch to impart regular traverse.

15. In a builder mechanism, the combination of a builder arm having a cam follower, a worm carried by the builder arm and confined to rotary movement relative thereto, a constantly rotated bunch building device movable laterally into bunch building relation with the worm and movable by the worm out of bunch building position on completion of the bunch, a loosely mounted main builder cam, means for holding the main builder cam from rotary movement with a low part of the cam opposite the cam follower during the bunch building operation, means for changing the relative positions of the bunch building device and worm towards and from each other to vary the position of the bunches on the bobbins, and means for causing rotary movement of the main builder cam on completion of the bunch to initiate regular service traverse.

16. In a builder mechanism, the combination of a builder arm having a cam follower, a worm carried by the builder arm and confined to rotary movement relative thereto, a constantly rotated bunch building device movable laterally into bunch building relation with the worm and movable by the worm out of bunch building position on completion of the bunch, a loosely mounted main builder cam, means for holding the main builder cam from rotary movement with a low part of the cam opposite the cam follower during the bunch building operation, means for changing the relative positions of the bunch building device and worm towards and from each other to vary the position of the bunches on the bobbins, and means for operatively connecting the main builder cam and rotating bunch building device on completion of the bunch to cause regular service traverse.

17. In a builder mechanism, the combination of a cam shaft, means for rotating it, a main builder cam loosely mounted on the

cam shaft, a builder arm having a worm, a bunch building device mounted on the cam shaft, for rotative movement therewith and lateral movement thereon to and from bunch building relation with the worm, means for holding the main builder cam from rotative movement and in predetermined rotative position during the bunch building operation, and means for cooperatively connecting the loose main builder cam with the rotating bunch building device on completion of the bunch to cause regular service traverse.

18. In a builder mechanism, the combination of a builder arm having a cam follower, a bracket on the builder arm, a worm carried by the bracket and confined to rotary movement, a constantly rotated bunch build-

ing device movable laterally into bunch building relation with the worm and movable by the worm out of bunch building position on completion of the bunch, a loosely mounted main builder cam, means for holding the main builder cam from rotary movement with a low part of the cam opposite the follower during the bunch building operation, means for adjusting the worm on the bracket towards and from the bunch building device to vary the position of the bunch on the bobbin, and means for rotating the main builder cam on completion of the bunch to cause regular service traverse.

19. In testimony whereof, I have signed my name to this specification.

JOHN A. SKEDGELL.
